UNITED STATES PATENT OFFICE.

EDWARD H. FOOTE, OF SOMERVILLE, MASSACHUSETTS, ASSIGNOR TO STANDARD ENVELOPE SEALER MANUFACTURING COMPANY, OF EVERETT, MASSACHUSETTS, A CORPORATION OF MASSACHUSETTS.

ENVELOPE-SEALING DEVICE.

1,417,897.

Specification of Letters Patent. Patented May 30, 1922.

Application filed June 16, 1920. Serial No. 389,477.

To all whom it may concern:

Be it known that I, EDWARD H. FOOTE, a citizen of the United States, and a resident of Somerville, in the county of Middlesex 5 and Commonwealth of Massachusetts, have invented a certain new and useful Improvement in Envelope-Sealing Devices, of which the following is a specification.

My invention relates to a type of envelope 10 sealer designed for use on the desk, it being the special object of my invention to make a small, light, and compact device which will be useful when there are a few envelopes to be sealed at a time as distinguished 15 from the usual envelope sealing machine which is designed to handle a large number of envelopes. Hence, it has been my aim to produce a device which shall be light and compact and which shall not encumber the 20 desk of the user when the device is not in use. It has been my further object to make such a device which shall be entirely efficient.

My device may be best understood by reference to the accompanying drawings in 25 which—

Fig. 1 is a top view.

Fig. 2 is a front view showing a stack of envelopes located in the device in process 30 of being sealed.

Fig. 3 is a top view showing an envelope with its flap in contact with the moistening device.

Fig. 4 is a section on line 4—4 of Fig. 3 35 viewed in the direction of the arrow.

Fig. 5 is a section on line 5—5 of Fig. 2 viewed in the direction of the arrow.

Fig. 6 is a cross section on line 6—6 of Fig. 4.

Referring now more specifically to the drawings, A is a base plate the front and back edges of which are curved downwardly and provided with rubber feet a. Passing through slots in the rear portion of base 40 plate A and riveted to the under side thereof are two upright posts B. A sealing plate C is superimposed upon the base plate A and slidably mounted in a manner whereby it may be elevated above base plate A by 45 means of slots through which pass the posts B.

The moistening tank D is securely fixed to the top of the sealing plate C. This tank

D is provided with a closely fitting cover d which has a slotted opening in its top 55 through the center of which passes an arched tongue E over which is looped a wick F, the dependent ends of which extend into the water in tank D. A hinged rod or flap depresser G of shape best illustrated in Fig. 60 1 is mounted on top of the cover d by means of straps g. The end of the rod G, most remote from the hinges formed by straps g, is held in a slightly elevated position by means of a boss H, thus permitting the insertion of the envelope flap between this rod or flap depresser G and the cover d of the moistener D.

The operation of my device is as follows: The flap of the envelope is opened and the 70 envelope is advanced by the hand of the operator with its flap forward and its face upward toward the moistener tank, the flap being inserted beneath the upturned end of rod G near the right side of the envelope. 75 The envelope is then further advanced and moved to the right causing the gummed edge of the flap to pass over the moistening wick F, the end of the rod or flap depresser G serving to hold the flap in constant moistening engagement with the wick F. When this moistening contact is completed, the envelope still held in substantially the same position, is inserted between the base plate A and sealing plate C, contact of the envelope flap with the downturned front edge of the base plate A causing the flap to be folded back into its normal position. The envelope is pushed between the base plate and the sealing plate until its advanced edge 80 contacts with the posts B. After the first envelope has been inserted successive envelopes may be similarly inserted excepting that it will usually be found to be more convenient to turn the flap downward and 85 against the body of the envelope by bringing it into contact with the front edge of the envelope or stack of envelopes protruding from between the curved front edges of the base plate and sealing plate. It will be 90 apparent that if the operator wishes to turn the envelope over before inserting it between the base plate and sealing plate the flap may be turned down by bringing it first into contact with the upturned front edge of the 105 sealing plate.

As the stack of envelopes grows it is apparent that the sealing plate C will rise to accommodate the stack by sliding upon posts B and that a desirable weight is given to the sealing plate C by the moistening tank D. If but few envelopes are handled at a time they may be conveniently left in the sealing stack until the user of the device is ready to mail or otherwise distribute them as such action will assist in the sealing operation by giving the moistened gum upon the flaps time to dry and harden. My device has the advantage over many hand sealing devices that the envelopes get a much longer sealing interval than that afforded by those devices wherein the moistened flap is passed rapidly between sealing plate or sealing rollers. I find this rapid sealing action to have little practical value, whereas a stack sealer of the character afforded by my device cannot fail to operate successfully, and the envelopes may be inserted into the compressed stack by reason of the relative positions of the moistening and sealing elements

and their peculiar structural features with 25 ease, rapidity, and certainty.

Having thus fully described my device, what I claim is,—

1. In a device of the character specified, the combination of a base plate, a sealing plate slidably mounted above said base plate in a manner whereby it may be elevated above said base plate and a moistener mounted upon said sealing plate.

2. In a device of the character specified, the combination of a base plate provided with a downwardly turned front edge, a sealing plate superimposed upon said base plate and provided with an upwardly turned front edge and a pair of slots located near 40 its rear edge, a pair of posts mounted on said base plate and extending through said slots and a moistener mounted upon said sealing plate.

In witness whereof I have hereunto affixed 45 my signature.

EDWARD H. FOOTE.
